UNITED STATES PATENT OFFICE.

JOHN KEARNEY, OF LOUISVILLE, KENTUCKY.

GUARD FOR TRAP-DOORS.

SPECIFICATION forming part of Letters Patent No. 427,427, dated May 6, 1890.

Application filed February 6, 1890. Serial No. 339,424. (No model.)

To all whom it may concern:

Be it known that I, JOHN KEARNEY, a citizen of the United States, residing at Louisville, in the county of Jefferson and State of Kentucky, have invented certain new and useful Improvements in Guards for Trap-Doors; and I do hereby declare the following to be a full, clear, and exact description of the invention, such as will enable others skilled in the art to which it appertains to make and use the same.

This invention relates to that class of devices which are designed to prevent persons from falling through doorways in sidewalks, floors, &c., when the doors are left open; and its object is, first, to provide guards for the sides of the doorway which shall be automatically placed in position for service by the act of opening the door; second, to provide a guard which may be fitted in front of the doorway whenever it is desirable to leave the door open, to prevent persons from falling through the doorway by carelessly or accidentally approaching its front, and, third, to provide means for adjusting a balance-weight to balance the weight of the door and its appendages.

To this end my invention consists in the construction and combination of parts forming a "guard for trap-doors," hereinafter described, and particularly set forth in the claims, reference being had to the accompanying drawings, in which—

Figure I is a perspective view of a trap-door or cellar-door in a sidewalk, showing my guards in position for service. Fig. II shows a central vertical section of the same with the door closed, &c. Fig. III shows the same with the door open, as looked upon from above. Fig. IV is an enlarged end view of the hinge-joint.

6 represents a trap-door, which may be of wood, sheet metal, wire-cloth, metallic bars, or other suitable material, hinged at 7 to a floor 8 or wall 9, to swing upward from a doorway which it covers in the floor. I provide this door with side guards 10, made of sheet metal, wire-cloth, or other suitable material and permanently secured to the under side of the door at its ends, to pass freely within the ends of the doorway when the door closes down.

11 represents the front guard, consisting of a frame comprising the cross-bar 12, the radial arms 13, the pendent bar 14, and suitable braces 15, and arms 16 17. The arms 13, 16, and 17 are joined as one piece, each such piece being the end of the frame and pivoted to the side guards 10 at 18 and further engaging the side guards by means of studs 19, which are rigidly fixed in the arms 17 and fitted to slide freely in slots 20 in said side guards, these slots being arcs of circles concentric with the pivots 18. The cross-bar 14 is rigidly fixed in the pendent arms 16. The braces 15 may be used in cases where much stiffness in the frame of the front guard is required. While the doorway is in service the frame 11 may be swung on its pivots 18 back out of the way.

21 represents arms provided with weights 22 and slotted at 23 to engage studs 24, which are fixed in the side guards 10. One or both of the studs 24 may be screw-bolts adapted to be loosened or tightened with a wrench, whereby the weights 22 may first be slid to the extension required to duly balance the door, so that it, with the attachments, may be easily raised, and yet not so far extended as to balance the door open undesignedly, and there be fixed by tightening one or both bolts. The hinge-pin 7 is a rod of iron extending entirely across the door and secured at its ends in bearings 25 at the sides of the door. If the door be made of sheet metal, as is most common for such doors, the edge of the metal is to be bent around the rod 7, as shown in Fig. 4, leaving a space under the front side for the edge of the hinge-cap 26 to enter. The hinge-cap is secured to an adjacent portion of the building and passes over the top and down in front of the hinge, forming a weather-strip to close the joint across the door, which is usually unprotected between the hinges of a door.

I do not limit myself to the exact construction herein described; but I may adopt any slight changes which do not materially deviate from the principle hereinbefore described, and particularly set forth in the following claims.

Having thus fully described my invention, what I believe to be new, and desire to secure by Letters Patent, is the following:

1. The combination of the door 6, provided

with a hinge 7 and with the side guards 10, secured to its under side, and further provided with curved slots 20, and the front guard 11, pivoted to the said side guards at 18 and provided with studs 19, fitted to slide in the slots 20, substantially as shown and described.

2. The combination of a hinged trap-door provided with the side guards having curved 10 slots in them, as described, and a front guard provided with radial arms pivoted to the said side guards and with studs to engage the said slots, substantially as shown and described.

3. The combination of a trap-door provided 15 with a hinge whose pivot-pin is a rod extending across the door, and further provided with a plate of sheet metal passing back under the said rod and up over it as a part of the hinge, and another portion of sheet metal secured to

the building and passing over the hinge-rod 20 and down around its front side, substantially as shown and described.

4. A trap-door hinge consisting of a hinge-pin long enough to cross the door, in combination with a plate of sheet metal extending 25 from the top of the door backward under and then upward over the said rod, and a hinge-cap adapted to be secured to the building and passing over and down around the front side of the said rod, substantially as shown and 30 described.

In testimony whereof I affix my signature in presence of two witnesses.

JOHN KEARNEY.
